US00D689998S

(12) **United States Design Patent**
Carbone et al.

(10) **Patent No.:** US D689,998 S
(45) **Date of Patent:** ** Sep. 17, 2013

(54) **DISPENSER HOUSING**

(75) Inventors: **Gabriele Carbone**, Lausanne (CH);
Khodayar Feiz, Amsterdam (NL);
Claudia V. Gamboa, Chicago, IL (US);
Jonathan N. Mandell, Gurnee, IL (US)

(73) Assignee: **S.C. Johnson & Son, Inc.**, Racine, WI (US)

(**) Term: **14 Years**

(21) Appl. No.: **29/430,188**

(22) Filed: **Aug. 22, 2012**

(51) LOC (9) Cl. **28-99**

(52) U.S. Cl.

USPC **D23/366**

(58) **Field of Classification Search**

(57) **CLAIM**

The ornamental design for a dispenser housing, as shown and described.

DESCRIPTION

FIG. 1 is an isometric view of a top, front, and left side of an ornamental design for a dispenser housing;

FIG. 2 is a front elevational view of the housing of FIG. 1; FIG. 3 is a rear elevational view of the housing of FIG. 1; FIG. 4 is a left side elevational view of the housing of FIG. 1; FIG. 5 is a right side elevational view of the housing of FIG. 1;

FIG. 6 is a top plan view of the housing of FIG. 1; and, FIG. 7 is a bottom plan view of the housing of FIG. 1. The dash-dash-dash broken lines are for the purpose of illustrating environmental structure and forms no part of the claimed design.

1 Claim, 6 Drawing Sheets

US D689,998 S
